[57] CLAIM

The ornamental design for plastic bag support rack having message board thereon, as shown and described.

DESCRIPTION

FIG. 1 is a top perspective view of a plastic bag support rack having a message board thereon showing our new design;

FIG. 2 is a front elevational view thereof;

FIG. 3 is a side elevational view thereof, the opposite side elevational view being a mirror image of that shown;

FIG. 4 is a top plan view thereof; and,

FIG. 5 is a bottom plan view thereof.

FIG.1

FIG. 2

FIG. 3

FIG. 4

FIG. 5
